UNITED STATES PATENT OFFICE.

ALEXANDER W. LAWRENCE, OF RALEIGH, NORTH CAROLINA.

DESIGN FOR SASH-HOLDER.

Specification forming part of Design No. 5,308, dated October 10, 1871.

To all whom it may concern:

Be it known that I, ALEXANDER W. LAWRENCE, of Raleigh, in the county of Wake and State of North Carolina, have invented a new and original Design for Sash-Lock and Holder; and I do hereby declare that the following is a full, clear, and exact description thereof, which will enable others skilled in the art to make and use the same, reference being had to the accompanying drawings forming part of this specification.

Figure 1 is a perspective view of the device when used to lock the lower sash down. Fig. 2 is a side elevation of the device when used to fasten the lower sash partly raised; and Fig. 3 is a side elevation of the device when supporting the lower sash fully raised.

This invention relates to the form of a lock of that class which is used for fastening down the

lower sash of a window, and also for holding the lower sash either wholly or partially raised.

Referring to the drawing, A is the body of the lock, the same having a straight front edge from *c* to *b*, a convex back edge from *d* to *e*, and a convex outer edge, *c d*. B is the fastener, the same having a convex edge, *e f*, and a straight face, *f g*. The fastener B enters a notch, *n*, formed in the side of the lower sash when the same is down and fastens it. C is the holder, the same having a straight face, *a b*, and an eccentric edge, *a h*.

What I claim as my invention is—

The design for a window-sash lock and holder, as herein shown and described.

ALEXANDER W. LAWRENCE.
